CLAIM

The ornamental design for a fan filtering portable spray
booth or similar article for use by graphic artists, as
shown.

DESCRIPTION

FIG. 1 is a front and right side perspective view of a fan
filtering portable spray booth or similar article for use
by graphic artists, showing my new design;

FIG. 2 is a front elevation view thereof;

FIG. 3 is a left side elevation view thereof;

FIG. 4 is a right side elevation view thereof;

FIG. 5 is a rear perspective view thereof;

FIG. 6 is a top plan view thereof;

FIG. 7 is a rear elevation view thereof; and,

FIG. 8 is a bottom plan view thereof.

fig.1.

fig.4.

fig.2.

fig.3.

Fig. 5.Fig. 7.Fig. 6.Fig. 8.
